Des. 203,208
Patented Dec. 14, 1965

203,208

MATTRESS CARRIER

Ernest C. Hillman, 831 S. Maryland St., Glendale, Calif.

Filed Sept. 4, 1964, Ser. No. 81,596

Term of patent 7 years

(Cl. D41—1)

Fig. 1.

Fig. 5.

Fig. 4.

Fig. 2.

Fig. 3.

FIG. 1 is a perspective view of a mattress carrier showing my new design;

FIG. 2 is a front elevation thereof;

FIG. 3 is a rear elevation thereof;

FIG. 4 is a side elevation thereof; and,

FIG. 5 is a top plan view thereof.

I claim:

The ornamental design for a mattress carrier, substantially as shown.
